DESIGN FOR A COMBINATION DESK UNIT

Alva R. Carver, Lakeland, Fla.

Application January 3, 1949, Serial No. 10

Term of patent 14 years

(Cl. D74—5)

To all whom it may concern:

Be it known that I, Alva R. Carver, a citizen of the United States of America, residing at Lakeland, in the county of Polk and State of Florida, have invented a new, original, and ornamental Design for a Combination Desk Unit, of which the following is a specification, reference being had to the accompanying drawing, forming a part thereof, wherein the figure is a perspective view of a combination desk unit, showing my new design, the side not shown and the rear portion being substantially plain.

The dominant features of my design reside in those portions shown in full lines.

I claim:

The ornamental design for a combination desk unit, as shown and described.

ALVA R. CARVER.
